LAST SUPPORT

Arthur F. Totz, Detroit, Mich.

Application October 3, 1935, Serial No. 43,290

5 Claims. (Cl. 12—127)

My invention relates to a new and useful improvement in a last support adapted for use in supporting shoe lasts and particularly as a support for shoe lasts for supporting the last while a sole or a half sole is being attached through the use of an adhesive material and a suitable pressure to the shoe.

It is an object of the present invention to provide a last support of this class which will be simple in structure, economical of manufacture, durable and highly efficient in use.

Another object of the invention is the provision of a last support having a supporting standard and a horizontally movable member slidably mounted in the standard so arranged and constructed that when the interior of the heel of the shoe is engaged the device will automatically tend to stretch the shoe by pulling the toe thereof outwardly of the last.

Another object of the invention is the provision in a last support of this class of a vertical standard having a horizontally movable arm provided with a spring for normally retaining said arm in one position relatively to the supporting standard and having a releasable mechanism engageable with teeth on said arm for locking the same in various positions of horizontal movement relatively to said standard.

Other objects will appear hereinafter.

The invention consists in the arrangement and combination of parts hereinafter described and claimed.

The invention will be best understood by a reference to the accompanying drawing, which forms a part of this specification, and in which,

Fig. 1 is a side elevational view of the invention with parts broken away and parts shown in section.

Fig. 2 is a fragmentary, sectional view taken on line 2—2 of Fig. 1.

Fig. 3 is a fragmentary, elevational view taken on line 3—3 of Fig. 1.

Fig. 4 is a side elevational view of the invention with parts broken away and parts shown in section with a heel-engaging member mounted on the supporting arm.

As shown in the drawing, the invention is used with a suitable table or supporting member 9 having upwardly projecting flanges 10 grooved out to provide a channel 11 in which will engage the base flange 13 of the vertical supporting standard 12. Formed through the standard 12 is a passage 14 in which slidably engages a supporting arm 15 having the recessed portion 16 on its under surface in which engages a spring

28. One end 19 of this spring is looped around a tongue 18 formed on the plate 17 which is secured to one face of the standard 12. The other end 21 of this spring is hooked around a pin 22 carried by the supporting arm 15. On one face of this supporting arm are formed the ratchet teeth 23. Mounted on one face of the standard 12 is a bracket 24 through which is slidably projected a plunger 25 having a head 26 which is adapted to project through the opening 26' into the passage 14. The inner end of the head 26 is provided with teeth 27 which are adapted to engage the teeth 23. A spring 28 embraces the plunger 25 and one end of this spring engages the bracket 24 and the other end engages the head 26 so as to normally tend to thrust the head 26 inwardly into engagement position as shown in Fig. 2. Fixedly mounted on the other end of the plunger 25 is the knurled knob 25' which serves as a gripping member for retracting the plunger. Projecting radially from the opening 26' is a stud 29 which, when the device is in the position shown in Fig. 2, engages in a slot 30 formed in the bracket 24 so as to prevent a rotation of the plunger. When the plunger is retracted it may be rotated so that the stud 29 will ride on the outer face of the bracket 24 and prevent engagement of the teeth 27 with the teeth 23.

In Fig. 4 I have shown a supporting post 32 slidably mounted in the opening or passage 31 which is formed in the supporting arm 15. Mounted swivelly by means of the pin 34 on the upper end of the post 32 is the heel-engaging head 33. The post 32 may be locked in its various positions of vertical adjustment by means of the set screw 35.

In use with the device as shown in Fig. 4 there is mounted on the standard 12 a last 36 having an opening 36' into which projects the stud 37 which extends upwardly from the upper face of the standard 12. This last 36 is also provided with a recess or pocket 38 in which engages the screw head 39 which projects outwardly from the upper face of the standard 12. This screw head prevents a rotation of the last on the stud 37. In use the shoe is placed over the last and over the heel-engaging head 33 and in order to place the shoe over the last the supporting arm 15 is moved horizontally so as to bring the post 32 into approach relatively to the standard 12 against the tension of the spring 29. When so positioned the plunger head 26 may be released to engage the teeth so as to prevent a movement of the supporting 55

arm 15. When the shoe is properly positioned, the plunger head 26 may then be pulled outwardly and the arm 15 will be moved in response to the action of the spring 20 so as to 5 force the post 32 outwardly and thus stretch the shoe tightly on the last 36. If the tension of the spring is not sufficient to properly stretch the shoe, it is obvious that the arm 15 may be further moved in the same direction, manually, 10 and the plunger head then released so that the teeth 27 will engage the teeth 23 and thus retain the arm 15 in its outwardly moved position.

In Fig. 1 I have shown the device used with a wooden last 44 which is mounted on the upper 15 end of the standard. This type of last is generally used with ladies' shoes. Slidably projected through the opening or passage 31 is a supporting post 40 having its upper end provided with the angularly-turned portion 41 terminating in the fork or supporting cradle 42 which is adapted to support the toe portion 43 of the last with the shoe thereon.

The flange 13 is provided with flat sides so as to prevent its rotation on the bed 9.

25 A last support constructed in this manner affords a device which is quite efficient, which permits of proper adjustment of the supporting arm 15 to its various positions, and which facilitates this movement so that a quick movement becomes possible. The use of the locking plunger and the spring 20 also affords a means of locking the arm 15 in its various positions and in addition quickly releasing and moving the same to other positions.

35 The teeth on the arm may be termed ratchet teeth and the plunger may be termed a ratchet pawl.

While I have illustrated and described the preferred form of construction, I do not wish 40 to limit myself to the precise details of structure shown, but wish to avail myself of such variations and modifications as may come within the scope of the appended claims.

Having thus described my invention, what I 45 claim as new and desire to secure by Letters Patent is:

1. A last support of the class described, comprising: a supporting standard having a passage formed therethrough, adjacent its upper 50 end; a supporting arm slidably projected through said passage; a spring connected to said arm and to said standard for normally resisting slidable movement of said arm relatively to said standard in one direction; teeth carried by said arm; a ratchet pawl mounted on said standard and projectable into engagement with said teeth for locking said arm against slid- 55 able movement relative to said standard, said plunger being retractable; a spring for normally tending to force said pawl into engagement with said teeth and resisting the retraction of the same and a shoe engaging member carried by said arm and positioned upwardly thereof.

2. A last support of the class described, comprising: a supporting standard having a passage formed therethrough, adjacent the upper 60

end thereof; a supporting arm slidably projected through said passage, there being an opening formed in said standard opening into said passage; teeth carried by said arm; a pawl mounted on said standard and projectable through said opening into said passage and adapted for engaging the teeth on said arm for locking said arm against movement relatively to said standard in one direction; a spring for normally retaining said pawl in engagement with said teeth; means for locking said pawl in non-engaging position and means carried by and projecting above said arm for engaging a shoe.

3. A last support of the class described, comprising: a supporting standard having a passage formed therethrough, adjacent its upper end, and provided with an opening at one side opening into said passage; a bracket spanning said opening and mounted on said standard and spaced outwardly therefrom at the portion projecting over said opening; a plunger slidably mounted in an opening formed in said offset portion of said bracket; a head on said plunger projectable through said opening; teeth on the inner face of said head; a spring for normally retaining said head projected inwardly of said opening; a stud projecting radially outwardly from said plunger and adapted upon the projection of said head into said opening for engaging in a slot formed in said bracket, said stud, upon the retraction and rotation of said plunger, engaging said bracket and locking said head against projection inwardly of said opening; a supporting arm slidably mounted in said passage; teeth carried by said arm and positioned opposite said opening and adapted for engagement with the teeth on said plunger and a shoe engaging member carried by and projecting upwardly from said arm.

4. A last support of the class described, comprising: a standard for supporting a last; a supporting arm slidably mounted on said standard below the upper end thereof and slidably transversely thereof; a shoe engaging member carried by and projecting upwardly from said supporting arm, adjacent one end; resilient means for resisting slidable movement of said arm relatively to said standard in one direction; teeth formed on said arm; and a pawl engageable with said teeth for resisting movement of said arm relatively to said standard in said direction.

5. A last support of the class described, comprising: a standard for supporting a last; a supporting arm slidably mounted on said standard below the upper end thereof and slidably transversely thereof; a shoe engaging member carried by and projecting upwardly from said supporting arm, adjacent one end; resilient means for resisting slidable movement of said arm relatively to said standard in one direction; teeth formed on said arm; and a spring pressed pawl engageable with said teeth for resisting movement of said arm relatively to said standard in said direction.

ARTHUR F. TOTZ.
